SHOT SHELL AND PROCESS OF MAKING
SAME

Edwin L. Johnson, Brownsburg, Quebec, Canada,
assignor to E. I. du Pont de Nemours & Company, Wilmington, Del., a corporation of Delaware

No Drawing. Application August 19, 1930, Serial
No. 476,435. In Canada March 6, 1930

2 Claims. (Cl. 91—68)

This invention relates to shot shells and processes of treating same and it comprises a shot gun shell having a paper body provided with a coating layer of cellulose ester composition in cohesive engagement and having the paper body impregnated interiorly with a waterproofing composition such as paraffin.

The main object of the invention is to provide shot shells which will be moisture proof and unaffected by atmospheric conditions; which can be fired in rapid succession without tending to stick in the hot gun barrel; which do not tend to stick in the breach; which are strong, durable and sufficiently rigid to withstand the rough usage to which shot shells are generally subjected in and out of the gun; and which are at the same time sufficiently elastic to allow for the necessary degree of expansion upon firing without liability to rupture.

Shot shells are usually made of cardboard or heavy paper. It is recognized that absorption of moisture creates difficulties of various kinds and particularly swelling. Any substantial absorption of moisture and swelling may render it difficult to handle a shell by the gun mechanism. Various methods of water proofing shells have been employed and various compositions have been used in rendering shells moisture proof. One method that has been successfully employed, is to first impregnate the interior of the shells with a water proofing composition such as paraffin and then after treating the surface of the paraffin shells, to coat same with a certain type of composition such as duco compositions in order to apply a coating that will remain in permanent cohesive engagement with the surface of the shell. Certain difficulties have been found in providing a composition that will bond or remain in cohesive engagement with a surface to which paraffin has been applied in order to obtain consistent results, special conditions are required as it is a well recognized fact that pyroxylin or other cellulose ester compositions, do not adhere satisfactorily under ordinary conditions, to a waxy or greasy surface owing to the tendency of the solvents used in such compositions to dissolve the grease, bring it to the surface of the film and prevent proper drying.

One of the objects of my invention is to obviate the difficulties heretofore encountered by

first applying the cellulose ester coating to the surface of the paper container and then after the coating has set to impregnate the paper container interiorly with a paraffin composition. I have discovered that penetration of a waterproofing composition such as paraffin into a paper shell or container is accomplished largely through the ends of the cardboard container, rather than through the cylindrical surface of same. While it is possible to penetrate the interior of a comparatively short paper shell through the ends of same, it will be obvious that a long shell could not thus be penetrated. A short shell, however, say of about the length of the ordinary shot shell, will when dipped in a bath become interiorly impregnated owing to the capillary action of the fibres on the waterproofing composition. The cellulose ester composition will bond much more readily with the surface of a paper container which has not been waterproofed or paraffined and the absence of wax or grease at this stage of the process enables me to use compositions without consideration of their solvent properties for grease. Further, I am not restricted to the use of pyroxylin or cellulose nitrate but may employ cellulose acetate or other cellulose ester.

My invention consists in reversing the steps of procedure and applying to the untreated surface of the paper container a cellulose ester composition and after same has dried to then apply to the ends of the shell a waterproofing composition such as paraffin, which will penetrate interiorly into the paper container by capillary action. A comparatively short shell or tube of the length ordinarily used in a shot gun shell will absorb sufficient paraffin to render it satisfactorily waterproof. As the paraffin composition is applied after the cellulose ester composition, the latter will bond and remain in cohesive engagement with the fibres of the shell much more effectively than if applied to a surface which has been subjected to a bath of paraffin. The amount of paraffin which is used for impregnating the paper container may be controlled.

While I prefer to use cellulose ester compositions which will bond cohesively with the fibres of the paper, much more latitude is permitted in the use of such compositions than if they were

applied to a surface which had previously been coated with wax. Generally, a composition containing a little drying oil and a certain amount of natural or synthetic resin is preferable.

5 I claim:

1. The steps of preparing a shot gun shell which consists in first coating paper shells with a cellulose ester composition and then impregnating the wall of the paper container between

the inner and outer surfaces with a paraffin composition.

2. The process of making paper shot shells which consists in applying to the surface of the paper container a cellulose ester composition and then impregnating the wall between the inner and outer surfaces of the paper shell with a paraffin composition.

EDWIN L. JOHNSON.
